SNOW PLOW

Arent M. Hegerland, Nevada, Iowa

Application August 30, 1954, Serial No. 452,826

7 Claims. (Cl. 37—45)

My invention relates to improvements in snow plows. One of the important objects of this invention is to provide a wheel mounted snow plow having various moving parts including conveyor means that are all operated by a drive means associated with the wheel assembly. In this respect my plow is designed to be pushed by a vehicle or manually depending on its size, so that no motor or other source of mechanical power for propelling the plow is required in the construction of the plow itself.

Another object of this invention is to provide a snow plow of the above class that has means for selectively discharging the gathered snow to either side of the plow relative to its direction of travel.

A further object of this invention is to provide a snow plow characterized by economy in manufacture, efficiency in operation and of a design adaptable for use on highways, side walks, driveways and private roads. In this regard it is one of my purposes to reduce the cost of such a plow by eliminating a motor mechanism and at the same time retaining certain mechanical aspects such as conveyors to reduce the effort involved whereby many persons, such as farmers with a private road, can economically afford a snow plow to quickly and easily handle their own snow removal problems.

Some of the other objects or purposes of this invention are to provide a snow plow of the above described type that is particularly adaptable for narrow roadways and can be designed for use thereon to adequately permit one way traffic while efficiently removing the snow and can because of its economy in manufacture be available to many sources such as small communities which may not otherwise have adequate snow removal equipment because of excessive costs.

These and other objects will be apparent to those skilled in the art.

My invention consists in the construction, arrangements, and combination, of the various parts of the device, whereby the objects contemplated are attained as herein-after more fully set forth, specifically pointed out in my claims, and illustrated in the accompanying drawings, in which:

Fig. 1 is a top plan view of my invention shown attached to the bumper of a vehicle,

Fig. 2 is a plan view partly in section taken on the line 2—2 of Fig. 5 to more fully illustrate the construction and arrangement of this snow plow,

Fig. 3 is a cross sectional view taken on the line 3—3 of Fig. 1,

Fig. 4 is a side view of this snow plow with portions in section taken on the line 4—4 of Fig. 1, and

Fig. 5 is a side elevational view of my new snow plow.

In order to more clearly understand the nature of this invention and a preferred means for carrying it out, reference is had to the drawings where like numerals are given to like parts. As shown, a framework or chassis indicated generally by the numeral 10 is formed by the spaced horizontal lower rails 12 and 14, the post or up-

2

standing members 16 and 18 secured or integrally formed at the rearward end of the respective rails 12 and 14 and the upstanding supports or posts 20 and 22 at the forward ends thereof. The forward posts 20 and 22 are of less height than the rearward posts 16 and 18 so that the upper rails or frame members 26 and 28 are on an incline as shown. Also the upper rails 26 and 28 project forwardly beyond posts 20 and 22 and a scoop member 30 is disposed between and supported by the forward ends thereof. Chassis 10 is made more rigid by braces 32, the cross bar 34 between posts 16 and 18 and other suitable braces as may be required and is further strengthened by certain of the operating parts as will later appear. Under each side of frame 10 at the rear is a wheel 36 of the caster variety and centrally positioned between the forward ends of the lower rails 12 and 14 is the drive wheel 38 which serves the dual function of supporting the frame 10 and providing the driving power that will be described later in detail. Wheel 38 is suitably mounted on a shaft or axle 39 that is vertically slidably disposed at its respective ends to the posts 20 and 24 and for this purpose the ends of shaft 38 are formed complementary in shape with the inner sides of posts 20 and 22 so as to be interlocking therewith as shown in Fig. 2 and designated by the numeral 40. A rack and pinion means 42 mounted on frame 10 and connected in a well known manner to axle 38 serves to raise or lower the frame to correspondingly change the position of scoop 30 relative to the ground and this is done by rotating handle 44. A pawl 46 (Fig. 4) is engageable with the pinion on assembly 42 to hold it against accidental movement.

A conveyor assembly 48 which moves longitudinally of top rails 26 and 28 comprises the belt 50 provided with spaced transverse cleats or flights 52. The belt is secured in a well known manner to the chains 54 which move over the rollers 56 that are secured to and between rails 26 and 28 in longitudinal spaced relationship. A sprocket 58 may be provided on the front and rear roller 56 for engagement with the chain 54 to assure against slippage when the belt is carrying a load and this is illustrated for the forward roller 56 in Fig. 5. No invention is claimed in such conveyor assembly per se as any suitable conveyor means for carrying snow from the scoop 30 may be employed.

At the upper rear portion of frame 10 are the oppositely disposed support plates 60 and 62 (Fig. 2) secured to or integrally formed with the respective posts 16 and 18 and are in effect a part of the frame structure for supporting certain parts as will be pointed out. A shaft or rod 64 rotatably secured to and between plates 60 and 62 carries a sleeve or collar 66 which is rotatable therewith and on which are mounted a pair of spaced sprockets 68. These sprockets are connected respectively by endless chains 70 to sprockets 72 (Fig. 4) secured at opposite sides of drive wheel 38 so that rotation of wheel 38 will rotate shaft 64 in the same direction therewith. A belt tightener in the form of the spring loaded idler sprocket 74 is associated with chain 70 in a well known manner as shown in Fig. 5 to keep the proper tension on that chain since it must be long enough to permit the movement of frame 10 by the rack and pinion 42 as above described. A clutch means 76 is associated with collar 66 and sprockets 68 for engaging or disengaging the same with drive wheel 38 and is manually operated by a lever control 78 mounted on plate 60.

A second shaft 80, to the rear of shaft 64, is rotatably disposed between plates 60 and 62 and has a central reduced portion 82 on which is mounted for rotation therewith the sleeve 84 carrying at each respective end the bevel gears 86 and 88. Sleeve 84 is shorter in length than the reduced shaft portion 82 and slidably between the

extremities thereof by a lever control means 90 as shown in Fig. 2. To the respective ends of shafts 64 and 80 and on the outer side of plate 62 is mounted the respective gears 92 and 94. Intermediate these gears 92 and 94 is a pinion or spur gear 96 which meshes with both of them and is suitably mounted to the outer side of plate 62 for that purpose so that shaft 80 will rotate in the same direction as shaft 64 and gear 96 will of course rotate in the opposite direction relative thereto. A stub shaft 98 projects coaxially from gear 96 and carries a pulley wheel 100 which is connected to a pulley wheel 102 on the rear roller 56 by the endless belt 104. By this arrangement, rotation of wheel 38 provides the power for moving conveyor assembly 48 so that on the top side of rollers 56, belt 50 is moving from front to rear to carry snow away from the scoop 30.

Extending from the rear of frame 10 is a frame extension member 106, which is pivotally secured to the lower ends of posts 16 and 18 as indicated at 108 and at the rear of frame 106 is the upstanding plate 110 or other suitable means to which the bumper 112 of a vehicle (not shown) can be secured by clamp 114 or the like for pushing this plow. In this respect, however, it will be understood that on a plow of this type designed for manual pushing the frame extension 106 will be formed as a suitable handle means. Spaced rearwardly of frame 10 and at the upper portion thereof is a snow deflector or shield 116 curved forwardly toward and extending higher than the rearward end of conveyor belt 50 which is secured to frame 10 by suitable braces or supports 118. Shield 116 is positioned transversely of the longitudinal plane of belt 50 and is preferably slightly wider than the distance between rails 26 and 28. Substantially coextensive in length with shield 116 is a second conveyor means 120 comprising spaced rollers 112 rotatably secured on a horizontal plane between cross bar 34 and the shield 116 on which is carried the belt 124. One of the rollers 122 is connected for rotation with a shaft 126 having a bevel gear 128 for selective engagement with the gears 86 and 88 to change the direction of movement of belt 124. Conveyor 120 is spaced below the rear end of conveyor 48 and will of course move transversely thereof.

In operation this snow plow is pushed forwardly into the snow and in this respect it is pointed out that at each side of the scoop 30 there is detachably mounted an upstanding blade or knife 130 for slicing through and loosening the snow in a swath corresponding to the width of the scoop. Also centrally positioned on the scoop is the upstanding divider 132 for further dividing the snow and breaking it up. An edge plate 134 on the scoop 30 is removable for sharpening as is well known in the art. Conveyor 48 will operate simultaneously with rotation of the drive wheel 38 and likewise the conveyor 120 at the rear will rotate at the same time by engagement of gear 128 with either gear 86 or 88. If with gear 86, conveyor will move to the right relative to the direction of travel and to the left if engaged with gear 88. Snow moving up conveyor 48 will drop onto conveyor 120 where it can be selectively discharged to either the right or left side. Extension units 136 (Fig. 3) may be provided for conveyor 120 in any suitable manner and geared by pinion 138 for moving in the same direction therewith. A guard or shield 140 (Figs. 4 and 5) at the rear of frame 10 will guide the snow falling from conveyor 48 onto conveyor 120.

Normally scoop 30 can be moved closely adjacent the ground if the snow is not too heavy and otherwise it can be elevated by the rack and pinion assembly 42 as above described. Clutch 76 can be used to disengage the drive wheel 38 from the conveyors 48 and 120 for road travel when the snow plow is not used as such.

It is pointed out that wheel 38 is preferably a large wheel with a rubber tire and can be provided with suitable chains or the like to increase traction when necessary.

In addition, the wheel 38 can be provided with different size sprockets to vary the speed of the conveyors as is well known in the art.

For the most efficient use of my snow plow it is intended that it be used to keep roads open in the early stages of a snow which it is apparent can be done most economically, and it is not expected to use this plow as a replacement for large machines capable of combating excessive drifts. Preferably I make this snow plow narrow enough to cover not more than one half of a roadway so as not to tie up traffic and at the same time to make it usable efficiently on roads other than main highways. Its principle of operation is simple, and the structure described is susceptible of manufacture in small enough units for manual operation so that it can be made available to persons now not ordinarily able to have such a piece of snow removal equipment.

It is submitted that the invention shown and described is aptly suited to achieve the purposes intended and is characterized by a combination of highly useful and mutually cooperating elements that combine their respective and proportionate functions in accomplishing the objects sought to be obtained.

Some changes may be made in the construction and arrangement of my snow plow without departing from the real spirit and purpose of my invention, and it is my intention to cover by my claims, any modified forms of structure or use of mechanical equivalents which may be reasonably included within their scope.

I claim:

1. A snow plow, comprising, a frame having an inclined surface lower at the front than at the rear, caster wheels for supporting the rear of the frame, a single drive wheel centrally arranged on said frame at its forward end, a scoop on said frame, a conveyor on said frame in line with said scoop, a first shaft rotatably journaled at the rear of said frame, drive means connecting said drive wheel to said first shaft, a second shaft rotatably journaled at the rear of said frame in spaced relationship to said first shaft, gears on corresponding ends of said first and second shafts, a spur gear on said frame intermediate said gears and meshing with both, and drive means connecting said second shaft to said conveyor.

2. A snow plow, comprising, a frame having an inclined surface lower at the front than at the rear, caster wheels for supporting the rear of the frame, a single drive wheel centrally arranged on said frame at its forward end, a scoop on said frame, a conveyor on said frame in line with said scoop, a first shaft rotatably journaled at the rear of said frame, drive means connecting said drive wheel to said first shaft, a second shaft rotatably journaled at the rear of said frame in spaced relationship to said first shaft, gears on corresponding ends of said first and second shafts, a spur gear on said frame intermediate said gears and meshing with both, drive means connecting said second shaft to said conveyor, and a frame extension projecting from the rear of said frame; said frame extension provided with a contact surface for engagement with a source of external power for pushing said plow.

3. A snow plow, comprising, a frame having an inclined surface lower at the front than at the rear, caster wheels for supporting the rear of the frame, an axle, the respective ends of said axle vertically slidably arranged to respective sides of said frame, means on said frame for vertically adjusting said axle, a single drive wheel centrally disposed on said axle, a scoop on said frame, a conveyor on said frame in line with said scoop, a first shaft rotatably journaled at the rear of said frame, drive means connecting said drive wheel to said first shaft, a second shaft rotatably journaled at the rear of said frame in spaced relationship to said first shaft, gears on corresponding ends of said first and second shafts, a spur gear on said frame intermediate said gears and meshing with both, and drive means connecting said second shaft to said conveyor.

4. A snow plow, comprising, a frame having an inclined surface lower at the front than at the rear, caster wheels for supporting the rear of the frame, an axle, the respective ends of said axle vertically slidably arranged to respective sides of said frame, rack and pinion means on said frame for vertically adjusting said axle, a single drive wheel centrally disposed on said axle, a scoop on said frame, a conveyor on said frame in line with said scoop, a first shaft rotatably journaled at the rear of said frame, drive means connecting said drive wheel to said first shaft, a second shaft rotatably journaled at the rear of said frame in spaced relationship to said first shaft, gears on corresponding ends of said first and second shafts, a spur gear on said frame intermediate said gears and meshing with both, and drive means connecting said second shaft to said conveyor.

5. A snow plow, comprising, a frame having an inclined surface lower at the front than at the rear, caster wheels for supporting the rear of the frame, a single drive wheel centrally arranged on said frame at its forward end, a scoop on said frame, a conveyor on said frame in line with said scoop, a first shaft rotatably journaled at the rear of said frame, drive means connecting said drive wheel to said first shaft, a second shaft rotatably journaled at the rear of said frame in spaced relationship to said first shaft, a sleeve slidable on said second shaft, a bevel gear on each end of said sleeve, means for sliding said sleeve, gears on corresponding ends of said first and second shafts, a spur gear on said frame intermediate said gears and meshing with both, and drive means connecting said second shaft to said conveyor.

6. A snow plow, comprising, a frame having an inclined surface lower at the front than at the rear, caster wheels for supporting the rear of the frame, a single drive wheel centrally arranged on said frame at its forward end, a scoop on said frame, a conveyor on said frame in line with said scoop, a first shaft rotatably journaled at the rear of said frame.

5 rear of said frame, drive means connecting said drive wheel to said first shaft, a second shaft rotatably journaled at the rear of said frame in spaced relationship to said first shaft, a sleeve slidable on said second shaft, a bevel gear on each end of said sleeve, means for sliding said sleeve, gears on corresponding ends of said first and second shafts, a spur gear on said frame intermediate said gears and meshing with both, and drive means connecting said second shaft to said conveyor.

10 15 20 25 30 35 40

10 posed at the rear of said frame to move transversely of said first mentioned conveyor, a snow deflecting shield extending upwardly and forward from the rear side of said second conveyor, and means for selectively operatively engaging the respective bevel gears on said sleeve with said second conveyor for moving it in two opposite directions respectively.

7. A snow plow, comprising, a frame having an inclined surface lower at the front than at the rear, wheels at the rear of said frame for supporting the same, a scoop on the forward end, an upstanding divider in the center of said scoop, an upstanding knife member at each side of said scoop, an axle vertically movable mounted to the forward end of said frame, a drive wheel centrally arranged on said axle, means on said frame for vertically moving said axle, a first shaft rotatably journaled at the rear of said frame, drive means connecting said drive wheel to said first shaft, a second shaft rotatably journaled at the rear of said frame in spaced relationship to said first shaft, gears on corresponding ends of said first and second shafts, a spur gear on said frame intermediate said gears and meshing with both, and drive means connecting said second shaft to said conveyor.
